5 Claims. (CL 123—184)

The present invention relates to a starting ignition device for multicylinder internal combustion engines.

In order to start internal combustion engines by ignition, the working ignition coil is with battery ignition, operated in known manner by a make and break device operated by hand or more usually electrically driven, whereby the ignition coil is either changed over from its working make and break device to a starting make and break device or the starting make and break device is connected in parallel to the working make and break device. In the first case there is the possibility, it is true, of effecting ignition in all positions in which the engine is at a standstill, but the danger of back-kicking is, of course considerable. In the second case in which the working make and break device operates the starting make and break device, danger of back-kicking is eliminated in as far as the duration of opening of the working make and break device only lasts until no spark can pass over from the distributor electrode to the segment succeeding the correct segment. It must, however, be taken into consideration that a spark can only be produced within a range predetermined by the working make and break device after the dead centre of the motor. It is desirable to keep this range comparatively small, more particularly with multi-cylinder motors in order to obtain sufficient closing time for the working ignition and as short as possible distributor segments. The disadvantages mentioned are eliminated according to the invention in that during the starting process the running ignition coil can transmit a series of sparks to the running electrode and a special starting ignition coil can transmit a series of sparks to the known starting electrode of the distributor.

The invention is illustrated in the drawings by several examples in which:—

Figure 1 shows the connection of a starting ignition device with a mechanical make and break device for starting.

Figure 2 shows a second connection with a trembler coil.

Figure 3 shows this second connection in which the trembler is controlled by the primary coil of the starting ignition coil.

Figure 4 is a connection with a trembler according to Figure 2 for alternately making and breaking the ignition coils.

Figure 5 is a connection with a trembler according to Figure 3 with intermittent interruption of the ignition coils.

Figure 6 shows a special slowing down position of the motor and the distributor.

In Fig. 1 a battery 1 is earthed at one pole and the other pole is connected to one contact of a unipolar ignition switch 2. One end of each of the two ignition coils 3 and 4, one at high tension and the other at low tension, are connected to the other contact of this switch. The other end of the primary winding 5, 6 is connected to each of two fixed contacts 7, 8 of a mechanically (Fig. 1) or electrically operated (Figs. 2-5) make and break device 10. In addition the end of the coil 5 is connected in the usual manner to a make and break device 9 which is operated by the engine. One of the condensers 11, 12 is connected in parallel to each make and break device. The other end of the secondary coil 13 is connected through the lead 27 to the working electrode 14 of the distributor 15 whilst the other end of the secondary coil 16 is connected through the lead 28 to a starting electrode 17 of the distributor. This starting electrode follows the working electrode through an angle determined by the number of cylinders and the required starting range.

The operation of the device is as follows:—

After a multi-cylinder internal combustion engine has been stopped one piston at least is always located past the upper dead centre so that its cylinder contains inflammable mixture. The piston A is at rest in this position (Fig. 1) and the working electrode 14 is thereby located in front of the distributor segment 18 belonging to this piston. The mixture in the cylinder can therefore be ignited directly by a spark from the working coil and the motor thereby put into operation. But it sometimes happens that the working electrode 14 comes to rest in front of a segment the respective piston of which has been brought to rest before the top dead centre. This case is shown in Fig. 6 and it is assumed that it is a five-cylinder motor. The working electrode 14 stands in front of the segment 30 which belongs to the piston B which stands before the top dead centre. There could be no starting with the working coil alone in this position, as the make and break device 9 must have been closed again for a long time because otherwise a spark could arise in the cylinder B and back-kicking of the engine thereby caused. It is however possible to start the engine by the starting electrode 17 with the present arrangement. The starting electrode 17 is so near to the segment 18, which belongs to the piston A which as a matter of fact lies at a fair distance from the top dead centre, that ignition can take place in the cylinder A. The spark

is produced by means of the starting coil 4 and the auxiliary make and break device (8, 10). No spark however is produced by the auxiliary make and break device 10 in the working coil 3 because the contact 7 is earthed through the make and break device 9 and the current in the winding 5 is not therefore interrupted. The danger of back-kicking is therefore excluded.

Fig. 2 shows the connection with an electric trembler 19. Two contacts 22, 23 which lie on the fixed contacts 7, 8 when the trembler is cut out, are mounted on the spring 20 together with the iron armature 21 of the trembler. The trembler coil 25 is connected on one side to the spring 20 and on the other side is earthed through the starting press button 24. The lead from the working coil 5 to the contact 7 is also operated by the press button 24 so that the starting coil does not lie permanently parallel to the working coil 20 when the trembler has stopped. The trembler simultaneously makes and breaks the two primary circuits of the ignition coils.

The construction according to Fig. 3 only differs from that according to Fig. 2 in that the primary winding of the starting coil acts also as trembler coil to the starting coil.

The construction according to Fig. 4 shows an arrangement wherein a trembler is provided for alternately switching on the primary coils 5 and 6. The fixed contact 7 of the working coil is separated from the contact 23 of the trembler armature when the trembler is at rest whilst the fixed contact 8 of the starting coil contacts with the contact 22 of the trembler armature. As soon as the press button 26 closes the circuit of the trembler coil 25, the spring 20 is drawn towards the core of the trembler and the contact 7-23 is closed and the contact 22, 8 is opened. The press button 24 with the double contact member can here be omitted because the coil is cut off from the trembler when the trembler is stopped. The construction according to Fig. 3 can of course be so made that the primary coil circuits are alternately broken. The corresponding connection is shown in Fig. 5.

I claim:

1. An ignition starting device for multi-cylinder internal combustion engines comprising in combination a running ignition system and a starting ignition system including an ignition coil connected in parallel with the ignition coil of the running ignition system, a battery connec-

tion, a trembler coil operating the starting ignition system and the running ignition system alternately, a switch for said trembler coil and a distributor electrode displaced from the distributor electrode of the running ignition system.

80

2. An ignition starting device for multi-cylinder internal combustion engines comprising in combination a running ignition system with a make and break controlled by the engine and a starting ignition system including an ignition coil connected in parallel with the ignition coil of the running ignition system, a battery connection, a trembler coil simultaneously operating the starting ignition system and the running ignition system for starting purposes, a switch for said trembler coil and a distributor electrode displaced from the distributor electrode of the running ignition system.

85

90

3. An ignition starting device for multi-cylinder internal combustion engines comprising in combination a running ignition system, a starting ignition system including an ignition coil connected in parallel with the ignition coil of the running ignition system, a battery for both systems, an interrupter adapted to make and break alternately the starting ignition circuit and the running ignition circuit, and a distributor including an electrode for the running ignition system and an electrode for the starting ignition system displaced from the other electrode.

100

4. An ignition starting device for multi-cylinder internal combustion engines comprising in combination a running ignition system with a make and break controlled by the engine, a starting ignition system including an ignition coil, a battery connection, an interrupter adapted to operate both the running and the starting system for starting purposes, and a distributor electrode for the starting ignition system displaced from the electrode of the running ignition system.

110

5. An ignition starting device for multi-cylinder internal combustion engines comprising in combination a running ignition system with a make and break controlled by the engine, a starting ignition system including an ignition coil, a battery connection, an interrupter adapted to operate both systems for starting purposes, said interrupter being operated by the starting ignition coil, and a distributor electrode for the starting ignition system displaced from the distributor electrode of the running ignition system.
